UNITED STATES PATENT OFFICE.

JAMES C. HENDERSON, OF PHILADELPHIA, PENNSYLVANIA.

DESIGN FOR A CART-BODY.

SPECIFICATION forming part of Design No. 35,868, dated April 15, 1902.

Application filed October 14, 1901. Serial No. 78,664. Term of patent 7 years.

To all whom it may concern:

Be it known that I, JAMES C. HENDERSON, a citizen of the United States, residing at Philadelphia, county of Philadelphia, and State of Pennsylvania, have invented and produced a new and original Design for a Cart-Body, of which the following is a specification, reference being had to the accompanying drawings, forming a part thereof.

10 Figure 1 is a side elevation of a cart-body. Fig. 2 is a front elevation of the cart-body; Fig. 3, a rear elevation of the cart-body.

15 My design consists in the angular body, the horizontal part A of which extends forward above the shafts, and the vertical portion C of the body drops from the rear of the horizontal part A downward and terminates with the floor D. This vertical portion C is formed narrower than the horizontal part A and 20 where it joins with this horizontal part is curved outward, as indicated at B. The vertical portion C is closed at this forward end, and this forward closed end extends vertically from the horizontal part A downward about two-thirds of the height of this closed

end and then is curved forward and downward at the point F and joins with the floor D.

The leading and material feature of my design consists in an angular body having a horizontal and vertical part, the vertical portion dropping below the horizontal part and being curved forward at the lower end and a roof or canopy covering the body. An opening G is formed through the rear of the body, and the body also consists of a roof or cover 30 H, which is connected to and supported by the horizontal part A by means of posts I.

Having described my invention, what I claim as new, and desire to secure by Letters Patent, is—

40 The design for a cart-body, as herein shown and described.

In testimony whereof I have hereunto affixed my signature in the presence of two subscribing witnesses.

JAMES C. HENDERSON.
